UNITED STATES PATENT OFFICE.

EDWARD GOTTLIEB, OF NEW YORK, N. Y., ASSIGNOR TO PARADOX ENGINEERING COMPANY, OF NEW YORK, N. Y.

MANUAL PAINTING MACHINE.

Application filed July 26, 1922. Serial No. 577,735.

To all whom it may concern:

Be it known that I, EDWARD GOTTLIEB, a citizen of the United States, residing in New York city, in the county of New York, State 5 of New York, have invented certain new and useful Improvements in Manual Painting Machines, of which the following is a full, clear, and exact description of the invention.

10 My invention relates to improvements in manual painting machines or machines for cleaning preparatory to painting, having movable members to spread the paint or clean surface to be painted; and the objects 15 of my improvements are, first, to produce a hand-guided painting machine with which a person can paint very much faster, and better than, and with more convenience, than with a plain paint brush, or any painting 20 machine previously invented, and the fundamental, basic idea I use to accomplish this is to construct a brush whose length is greater than its width, said brush to have mechanical means for moving bristles comprising the brush, (constructing a brush of any 25 desirable length without the width becoming bulky aids greatly in the rate of spreading paint, under various conditions, and a thorough system of distributing the paint 30 uniformly over the entire length of brush, regardless of the length gives my painting machine the great advantage of delivering an even coat of paint to the surface to be painted); second, to produce a brush of the 35 revolvable member type of any desirable length without the width becoming bulky, so that the area to be painted, or cleaned, or prepared to be painted will be covered quickly. For purpose of illustration I will 40 pick some particular cases, suppose the side of a ship, or a large flat wall is to be painted, in this case it may be desirable to use a brush 12" or 15" long and about 2" wide, but if the interior of a room is to be painted 45 it may be desirable to use a brush 5" long and 2" wide, and suppose a very irregular object is to be painted it may be desirable to use a brush 2½" long and 1" wide, and suppose some standard object of a definite shape 50 is to be painted in quantity it will be desirable to construct a brush of any desirable shape to fit this particular object, and from the accompanying drawings and specification it is readily seen that my brush can be 55 adapted to any shape. (as before stated in

conjunction with this long brush of small width, are means for moving the bristles composing the brush so that the linear speed of the moving bristles is in excess to the linear speed of a man moving an ordinary paint brush, this aids greatly to the speed of spreading the paint); third, to provide for a brush of the character mentioned manually operated means for controlling the supply of paint; fourth, to provide for a brush of the character mentioned means of rotating revolvable members; fifth, to provide for a brush of the character mentioned means of spreading the paint uniformly; sixth, to have a brush as light 60 as possible so that it can be readily handled and thus aid to the convenience of spreading the paint, and from accompanying drawings it will be seen that I accomplish this by the use of a flexible wire drive to the 65 brush, so that the driving mechanism to operate the revolvable member is external to the brush; seventh, means to prevent brushes of the revolvable member type 70 from throwing paint centrifugally. 75

One embodiment of my invention is illustrated in the accompanying drawings, in which like characters of reference denote corresponding parts in all the views, (and when in any part of this patent application I 80 refer to "the brush" or "the painting brush" it must be understood to mean the entire portion of the painting machine that is held in the hand, see Figure 5 of the accompanying drawings, when I refer to the rotating 85 brushes I will always add some modifier to indicate same, as "the small brushes," "rotating brushes" etc.) and in which—

Figure 1 is a front view of a machine containing a preferred form of my invention; Figure 2 is a vertical section taken on the line AA; Figure 3 is a longitudinal section taken on the line BB; Figure 4 is a view of the back of the machine with cover 76 off, and Figure 5 is a perspective view of a hand holding the painting brush in the same position as when brush is in operation. This figure also shows paint supply line, air supply line, and small brush rotating line.

The brush consists of a number of small 105 brushes 1, 2, 3, 4, and 5, which are longer than wider as shown, and which are held to the small brush seats 6, 7, 8, 9, and 10 by means of small springs 11, 12, 13, 14, 15, and 16. The small brushes 1, 2, 3, 4, and 5 110

are readily detachable so that when they are worn out, they can be easily replaced by new ones. These small brushes have little pins 17, 18, 19, 20, 21, and 22 projecting out of the backs and engaging in holes in the small brush seats, helping to hold the small brushes in place. The small brush seats are fastened to gears 23, 24, 25, 26, and 27. These gears are of the shape shown in accompanying drawings and have bearings in the brush body 28.

These gears mesh with each other and are so timed that the attached brushes are at right angles to each other. When the small gear 29 turns, it will rotate gear 25 in a certain direction, and in turn gear 25 rotates gears 24 and 26 in the opposite direction, and these in turn rotate gears 23 and 27 in the opposite direction to themselves.

It is simple to understand that because the attached brushes are at 90° from each other, and since they are longer than wider as shown on accompanying drawings, and since adjacent gears turn in opposite directions, the attached brushes will not interfere when rotating, and at the same time their painting areas will overlap. By using a different number of brushes, as 2, 3, 4, etc. the brush can be made any desirable length without the width of the brush becoming bulky. Small gear 29 is driven by a flexible wire 30, which some prime mover 31 drives at the other end, (as an electric motor, or air motor). This flexible wire runs inside of a stationary flexible tube 31^a. It is desirable to make both the tube and wire in sections, say 6 feet long, coupled together, so that for any particular job the length can be convenient. A shaft 32 of the small gear 29, has a bearing and coupling 33, and another bearing at the other end 34.

There is a stationary fringe of brush 35 to catch any paint that might be thrown centrifugally by the small rotating brushes. This stationary fringe of brush is held to the brush body 28 by means of straps 36, 37, 38, and 39, and also by a number of pins 40, and 41. This fringe of brush is readily detachable so that when it gets worn out from service, it may be replaced by new ones.

The pipe 42 leads the paint from a paint supply to the brush. It is preferable to have the paint under pressure so that there is a ready flow. One convenient method of getting paint under pressure is to have a paint can 43, having an air tight cap 44, which can be removed and can be filled partly with paint. The cap 44 is then put on again and a hand air pump is connected with the one way valve 45. It is very easy to raise the pressure inside of the paint can so that the paint will flow readily. It is advisable to have a filter 46 to catch any dirt or lumped paint which may be in the paint.

To control the paint as it enters the brush,

there is a valve 47. When the valve is open the paint flows up pipe 48 and into the main pipe 49 inside of the brush. This main pipe has smaller pipes 50, 51, 52, 53, and 54, branching off to supply paint to each of the small rotating brushes separately. There are small valves 55, 56, 57, 58, and 59 in each of these branch pipes so that the amount of paint can be regulated for each small brush separately. The paint supply pipes 50, 51, 52, 53, and 54 terminate in nozzles 60, 61, 62, 63, and 64. These small pipes run inside of larger pipes 65, 66, 67, 68, and 69 which are for compressed air and which terminate in nozzles also. The paint nozzles are inside of the air nozzles, this construction helps to draw, atomize and spray the paint against the surface to be painted, thus insuring a more even spread of paint. These larger pipes for the air are branches from the main pipe 70, which is supplied with compressed air from pipe 71 in which is a regulating valve 72, and leads via pipe 73 to a compressed air supply 75.

There is a back cover 76 on the brush. Each gear 23, 24, 25, 26, and 27 must be lubricated at the bearings, and for this purpose grease cups 77, 78, 79, 80, and 81 are necessary. Each gear has a small hole 82 to allow some grease to flow down and lubricate the contact between the moving gear and the stationary large air pipes. It is advisable to bind the three pipes together 83, for convenience as shown in Figure 5.

The operation of the painting machine is as follows:—The brush is held in one hand, and with the other hand the operator starts the prime mover, which transmits its rotation via the flexible wire to the small rotatable brushes. Then with the free hand the operator opens the air valve 72. The small brushes are now rotating and the air flowing, then the operator puts the brush against the surface to be painted. He next opens the paint valve 47, with his free hand, and starts painting, by passing the brush over the surface to be painted. The small valves 55, 56, 57, 58 and 59 are adjusted so that the paint is spread evenly. Due to the speed of the small rotating brushes the linear distance covered in a given time by each small brush is very great, when compared with the linear distance covered by a man having a plain ordinary painting brush, therefore my painting machine can paint very much faster, and due to the well distribution of the paint, and the rotating brushes, my paint machine makes a very good spread of paint. When the machine is to be used to clean a surface preparatory to painting, a cleaning fluid is used instead of the paint.

Having thus described my invention, I claim as new:—

1. In a painting machine, or machine for cleaning, preparatory to painting, of the

- character described, a brush composed of a number of small rotatable brushes so arranged and so constructed that each other's painting area overlaps, thus forming a long brush of small width; a brush having a paint supply to each small rotatable brush, individually controlled by separate valves; hollow gears and hollow small brushes to permit the paint supply to be lead to the front of brush, the ends of the paint supply pipes in the small rotatable brushes to be equipped with nozzles so that the paint under pressure is forced against the surface to be painted; a compressed air supply to each small rotatable brush, circumfolding the paint supply pipes and terminating at the ends in a constricted nozzle within which is the paint supply pipe nozzles, to help draw, spray, and atomize the paint, and impinging it against the surface to be painted; a flexible wire drive for small rotatable brushes with driving mechanism to rotate wire external to brush; and a brush having a stationary fringe of brush enclosing small rotatable brushes to catch paint thrown centrifugally by the rotating brushes. 2. In a painting machine and a machine for cleaning surfaces to be painted, of the character described, a brush composed of several small rotatable brushes adjacent to each other and of such shape that when rotating, each other's painting areas overlap, producing a brush of any desired length and small width; means for detaching small rotatable brushes; a flexible wire transmitting a rotatory motion from some external prime mover to the small rotatable brushes; rotating flexible wire being protected in a flexible tube; a gear for each small brush meshing with adjacent gear from adjacent brush, and brushes so timed that they do not interfere when rotating and that their painting areas overlap; a stationary line of bristles around rotatable brushes to catch paint thrown centrifugally; means for detaching and replacing stationary line of bristles around rotatable small brushes; a paint supply using paint under pressure; separate paint nozzles and compressed air nozzles for each small rotating brush to force paint against surface to be painted; control valves to adjust the amount of air supplied to brush; control valves to adjust the amount of paint supplied to brush. 3. In a painting machine, or a machine to clean surfaces to be painted, of the character described, the combination of, a brush composed of a multiple of small revolvable brushes so constructed that each other's painting areas overlap, thus forming a long brush of small width; and a paint supply or cleaning fluid line to each small revolvable brush individually controlled by separate valves; and a compressed air supply line to each small revolvable brush circumfolding the paint supply line; and the paint supply line terminating in nozzles circumfolding the air supply line nozzles; and valves to control the supply of air; and a wire in a flexible tube to drive revolvable member that spreads the paint or cleans surface to be painted; and an external mechanism to drive other end of wire; and a stationary row of bristles around small rotatable brushes to catch paint, or dirt thrown centrifugally. 4. In a painting machine or machine to clean surfaces preparatory to painting, of the character described, a brush composed of a couple or more small elliptically shaped brushes, timed so that the long axis of one elliptical shaped brush being at right angles to the long axis of the adjacent elliptically shaped brush and that in turn being at right angles to the next adjacent brush, etc., so that each other's paint areas overlap and the small brushes do not interfere when rotating; a train of gears meshing and having the small elliptically shaped brushes attached, said train of gears being driven from small pinion receiving its rotation motion from a wire drive; a wire drive being driven by external prime mover; a paint supply to each small rotatable brush controlled by valves; a compressed air supply line controlled by valves; a paint nozzle and a compressed air nozzle, to aid in atomizing and spraying the paint; and a stationary fringe of brush as shown in attached drawings. 5. In manual painting machines or machines to clean surfaces, a brush so constructed that its length is greater than its width, and mechanical means for moving the bristles of brush, so that the linear speed of the bristles is great when compared with the linear speed possible with an ordinary plain painting brush; a paint supply line manually controlled; and paint nozzles infolded in compressed air nozzles to atomize and spray the paint against surface to be painted. 6. A painting machine or machine to clean surfaces described, having a brush composed of small rotary brushes; means for detaching and replacing small rotatable brushes; a driving mechanism external to brush to rotate small brushes, using a wire transmission; a wire transmission to convey a rotatory motion from some external source to the small rotatable brushes; a paint delivery mechanism adapted to deliver paint in a spray; manually-controlled means for controlling the said paint-delivery mechanism; a stationary row of bristles to catch paint thrown centrifugally by rotating brushes; and means for detaching and replacing stationary fringe of bristles. 7. In hand operated painting machines or machines to clean surfaces to be painted, having a revolvable member to spread the

paint or clean surface to be painted, a rotatable flexible wire in a stationary flexible tube, to rotate the revolvable member used to spread the paint, and an outside driving mechanism being used to give the rotatable wire its rotation, a stationary fringe of brush circumfolding the revolvable member or members to catch paint thrown by the revolvable member, or members, and means 10 for replacing stationary fringe of brush.

8. In manual painting machines or machines to clean surfaces to be painted, having a revolvable member to spread the paint or clean surfaces to be painted, a wire to 15 transmit rotating motion to the revolvable

member, and a stationary protecting tube circumfolding rotating wire, flexible wire transmitting rotation to revolvable painting member from some external driving mechanism, thus making a very light painting machine; a stationary row of bristles around revolvable member to catch paint, or dirt thrown centrifugally; and means for detaching and replacing stationary row of bristles around revolvable member. 20
